(No Model.)

E. D. CHILDS.
SHOE NAILING MACHINE.

No. 443,357.

Patented Dec. 23, 1890.

Fig. 1.

Fig. 3.

A technical drawing of a mechanical assembly, labeled 'Fig. 4.' in a cursive script. The drawing shows a central vertical cylinder with a circular base. On the left side, there is a circular component with a ribbed outer edge, labeled with the letter 'K'. On the right side, there is a rectangular housing with a ribbed outer edge, labeled with the letter 'E'. Various other parts are labeled with letters such as 'K'', 'G', 'J', 'E''', 'H', 'G''', 'G''', 'G''', 'K''', 'J', and 'E'''. The drawing uses hatching and cross-hatching to differentiate between different parts of the assembly.

UNITED STATES PATENT OFFICE.

EDWARD D. CHILDS, OF MILWAUKEE, WISCONSIN.

SHOE-NAILING MACHINE.

SPECIFICATION forming part of Letters Patent No. 443,357, dated December 23, 1890.

Application filed August 23, 1890. Serial No. 362,812. (No model.)

To all whom it may concern:

Be it known that I, EDWARD D. CHILDS, of Milwaukee, in the county of Milwaukee, and in the State of Wisconsin, have invented certain new and useful Improvements in Feed Mechanism for Shoe-Nailing Machines; and I do hereby declare that the following is a full, clear, and exact description thereof.

My invention relates to shoe-nailing machines; and the invention consists in certain peculiar and novel features of construction and arrangement, as hereinafter described, and pointed out in the appended claims.

In the drawings, Figure 1 is a view, partly inside elevation and partly in transverse vertical section, of a structure embodying my invention. Fig. 2 is a horizontal cross-section of the same on the line 2 2 of Fig. 5. Fig. 3 is a similar view on the line 3 3 of Fig. 1. Fig. 4 is a similar view on the line 4 4 of Fig. 5. Fig. 5 is an enlarged view, partly in side elevation and partly in vertical cross-section, of my improved feeding mechanism.

The object of my invention is to provide a feeding mechanism for boot or shoe nailing machines which shall be practically continuous in its operation, and which can be run at high speed without becoming injured or disordered in any of its parts. This result I attain by virtue of the construction which I will now proceed to describe.

Referring to the drawings, A designates a spindle the upper end of which is preferably externally screw-threaded, as at a, to receive an internally-screw-threaded pulley B, which by means of a suitable belt constantly rotates the spindle axially. This spindle is also formed with a central longitudinal channel or bore a', which extends throughout its length, and its lower end is formed with a screw-threaded socket a² to receive the externally-screw-threaded upper end of a throat-piece C, the said throat-piece having also a central longitudinal bore c, which coincides with the bore of the spindle. The pulley B carries on its upper side two brackets D, between which is journaled a reel D', upon which the wire stock E is wound, the strand e of the stock (which may be threaded, twisted, corrugated, or any other wire) extending downward through the bores a' c of the spindle and throat-piece, respectively. The lower end of

the spindle A is bifurcated to form two bearing-plates E' E', in the lower part of which are formed half-sockets e' e' for the two lower feed-rolls F F, the journals of said rolls being in the lower ends of the oppositely-disposed presser-plates G G and G', which are screwed upon opposite sides of the bearing-plates E' E', as shown at g g'. A guard-plate or shield H is preferably interposed between the presser-plate G' and the adjacent edges of the bearing-plates E', and said guard-plate or shield is secured in position by screws h. The protruding ends of the journals of feed-rolls F carry intermeshing gear-pinions f f, with one of which meshes a gear-pinion I, which is journaled upon a screw-stud i, protruding from the adjacent bearing-plate E'.

J designates a worm-gear, the shaft j of which is journaled in half-sockets in the presser-plates G, and also in the adjacent edges of the bearing-plates E'. The protruding end of the shaft j carries a gear-pinion J', which meshes with the gear-pinion I, before referred to.

K designates a worm-shaft, the worm k of which meshes with the worm-wheel J, and the lower end of which is stepped into a strap k', which is attached to the presser-plates G G by screws k², as is best shown in Fig. 4. The upper part of this worm-shaft extends through an offset m of a collar M, which surrounds the spindle A just above the bearing-plates E', and which is secured in position upon the spindle A by a set-screw m', so as turn therewith, and jam-nut m². Within the offset m the worm-shaft K is formed with an annular recess k³, which is engaged by the inner end of a set-screw m³, having a jam-nut m⁴, and serving to retain the worm-shaft in proper position while at the same time permitting it to rotate.

At its upper end the worm-shaft K carries a gear-pinion N, which meshes with a gear-section o on the lower end of a sleeve O. This sleeve O surrounds the spindle A immediately above the collar M, and at its upper end it is formed with an offset O', having a number of radially-arranged holes or recesses o', for a purpose to be hereinafter explained.

P designates an E-shaped standard, having at its upper end a bearing or hub p and midway of its length a similar hub or bearing p',

the spindle A extending through said hubs or bearings. The lower end of this standard has an opening p^2 to receive the throat C, and also carries a suitable knife P' to sever the wire after each nail has been driven. Upon the end of the upper arm of standard P is journaled a cam-disk Q, which carries a worm-wheel q, the teeth of which mesh with a worm q' on the spindle A. Upon an arm r, which extends from the hub p', is pivoted midway of its length a lever S, the upper end of which carries a friction-roller s, which is held against the cam-shaped periphery of the cam-disk Q by a leaf-spring s' or equivalent means. The lower end of this lever carries a pin t, which works in an opening in an arm t', projecting from the hub p', before referred to.

The operation is as follows: The spindle A revolves constantly and its worm q' rotates the cam-disk Q. As long as the friction-wheel s is in the depressed portion of the periphery of the cam-disk, pin t is held out of engagement with the sleeve O, and thus the feed mechanism is inoperative; but when the friction-wheel rides upon the projecting portion of the periphery of this disk the pin t is moved into one of the holes or recesses o'. This causes the gear-section o of sleeve O to remain stationary, while the collar M, rotating with the spindle A, turns shaft K, this causing the gear N to rotate the worm-shaft K, and this, through its worm k, turns the worm-gear J, the result being that motion is communicated to the gear-wheels J' and I, and then through the gears f f to the feeding-rolls F F, so that the lower end of the wire is quickly forced into the sole of the shoe held on the ordinary horn R. By this time the friction-wheel s rides inward onto the depressed portion of the cam-disk Q, the pin t is withdrawn from engagement with the sleeve O, and the feed is stopped long enough to permit the stock to be severed. The subsequent operations are repetitions of those just described.

It is obvious that minor details of construc-

tion may be changed without affecting the essential spirit of my invention as set out in the appended claims.

Having thus fully described my invention, 50 what I claim as new, and desire to secure by Letters Patent, is—

1. In a feed mechanism for shoe-nailing machines, a rotary spindle, intermeshing geared feed-rolls mounted at the lower end of the 55 spindle, a train of gear-wheels also located at the lower part of the spindle and meshing with the feed-roll gears, a worm-shaft mounted on the lower part of the spindle and carried thereby and operatively engaging a 60 worm-gear on the axle of one of the feed-roll-actuating train-gears, a sleeve loosely surrounding the spindle and geared to the worm-shaft, a cam-disk actuated by the spindle, and a lever operatively engaging the disk at 65 one end and at its opposite end intermittently engaging the said sleeve, substantially as set forth.

2. In a feed mechanism for shoe-nailing machines, a rotary spindle, intermeshing geared 70 feed-rolls mounted in the lower part of the spindle, a train of gear-wheels meshing with the feed-roll gears, a worm-shaft mounted on the lower part of the spindle and carried thereby and meshing with a worm-pinion on the 75 shaft of one of the train-gears, a sleeve loosely mounted upon the spindle and having a gear meshing with a gear upon said worm-shaft, and means, substantially as described, actuated by the spindle and serving to intermittently connect and disconnect the sleeve from operative engagement with the spindle, substantially as set forth.

In testimony that I claim the foregoing I have hereunto set my hand, at Milwaukee, in 85 the county of Milwaukee and State of Wisconsin, in the presence of two witnesses.

EDWARD D. CHILDS.
